(57) **CLAIM**

The ornamental design for a lidar, as shown and described.

DESCRIPTION

FIG. 1 is a perspective view of a lidar showing my new design according to a first embodiment.

FIG. 2 is a front view of the lidar of FIG. 1.

FIG. 3 is a rear view of the lidar of FIG. 1.

FIG. 4 is a right-side view of the lidar of FIG. 1.

FIG. 5 is a left-side view of the lidar of FIG. 1.

FIG. 6 is a top view of the lidar of FIG. 1.

FIG. 7 is a bottom view of the lidar of FIG. 1.

FIG. 8 is a perspective view of a lidar showing my new design according to a second embodiment.

FIG. 9 is a front view of the lidar of FIG. 8.

FIG. 10 is a rear view of the lidar of FIG. 8.

FIG. 11 is a right-side view of the lidar of FIG. 8.

FIG. 12 is a left-side view of the lidar of FIG. 8.

FIG. 13 is a top view of the lidar of FIG. 8.

FIG. 14 is a bottom view of the lidar of FIG. 8.

FIG. 15 is a perspective view of a lidar showing my new design according to a third embodiment.

FIG. 16 is a front view of the lidar of FIG. 15.

FIG. 17 is a rear view of the lidar of FIG. 15.

FIG. 18 is a right-side view of the lidar of FIG. 15.

FIG. 19 is a left-side view of the lidar of FIG. 15.

FIG. 20 is a top view of the lidar of FIG. 15.

FIG. 21 is a bottom view of the lidar of FIG. 15.

FIG. 22 is a perspective view of a lidar showing my new design according to a fourth embodiment.

FIG. 23 is a front view of the lidar of FIG. 22.

FIG. 24 is a rear view of the lidar of FIG. 22.

FIG. 25 is a right-side view of the lidar of FIG. 22.

FIG. 26 is a left-side view of the lidar of FIG. 22.

FIG. 27 is a top view of the lidar of FIG. 22; and,

FIG. 28 is a bottom view of the lidar of FIG. 22.

The portions of the lidar shown in shown broken lines are for illustrative purposes and form no part of the claimed design.
